US00D665332S

(12) **United States Design Patent**
Vicente et al.

(10) **Patent No.:** US D665,332 S
(45) **Date of Patent:** ** Aug. 14, 2012

(54) **AIRCRAFT**

(75) Inventors: **Paulo Jorge Pires Vicente**, Chainça (PT); **Cassiano Dos Santos Rodrigues**, Oporto (PT)

(73) Assignee: **Nortavia—Transportes Aereos S.A.**, Vermoim Maia (PT)

(**) Term: **14 Years**

(21) Appl. No.: **29/406,947**

(22) Filed: **Nov. 21, 2011**

(51) LOC (9) Cl. **12-07**

(52) U.S. Cl. **D12/319; D12/323**

(58) **Field of Classification Search** D12/327, D12/326, 328, 329, 330, 319, 343, 324, 323; 244/96, 29, 26, 25, 17.17, 116, 115; D23/377; D21/827, 583, 558, 453, 442, 440

See application file for complete search history.

(57) **CLAIM**

We claim the ornamental design of an aircraft, as shown and described herein.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is a front view of the aircraft showing our new design;

FIG. 2 is a top view thereof;

FIG. 3 is a side view thereof;

FIG. 4 is a top and font perspective view thereof; and,

FIG. 5 is a top and rear perspective view thereof.
